UNITED STATES PATENT OFFICE.

GEORGE H. BELL, OF WHITE SULPHUR SPRINGS, MONTANA.

COMBINED PUMP-SPOUT AND DRINKING-FOUNTAIN.

1,295,677.

Specification of Letters Patent. Patented Feb. 25, 1919.

Application filed October 31, 1918. Serial No. 260,576.

To all whom it may concern:

Be it known that I, GEORGE H. BELL, a citizen of the United States, residing at White Sulphur Springs, in the county of Meagher and State of Montana, have invented certain new and useful Improvements in Combined Pump-Spouts and Drinking-Fountains, of which the following is a specification.

10 This invention relates to improvements in the discharge spouts of pumps, and has for one of its objects to provide a sanitary drinking fountain attachment to devices of this character.

15 Another object of the invention is to provide a sanitary drinking fountain attachment to a pump spout so arranged that it does not interfere with the ordinary uses of the spout.

20 With these and other objects in view, the invention consists in certain novel features of construction, as hereinafter shown and described, and then specifically pointed out in the claims; and in the drawings illustrative of the preferred embodiment of the invention—

Figure 1 is a side elevation, partly in section, of the improved device.

Fig. 2 is a detail partly in section, illustrating a modification in the construction.

The improved device may be applied without material structural change to pumps of various forms, and it is not desired to limit the invention in any manner in this respect. For the purpose of illustration the improved spout is shown applied to a conventional pump in which 10 represents a portion of the cylinder or body of the pump. The pump cylinder is formed

40 with a spout receiving base 12, and the improved spout is provided with an attaching flange detachably secured to the base by bolts or other fastening devices 13, thus replacing the ordinary spout.

45 The improved spout comprises a tubular body 14 having a downwardly directed discharge 15 and provided with a cut-off valve represented as a whole at 16. The body 14 is provided with a threaded boss 17 which

50 supports a vertical conductor tube 18. Attached to the tube 18 is a receiver or reservoir 19, preferably globular in shape, there being a pipe section 20 threaded on the upper end of the conductor 18 with its terminal spaced from the upper end of the reservoir, as shown. The reservoir is pro-

vided with a closure cap 21 to render the interior of the reservoir accessible for cleansing, and likewise to permit the parts to be coupled.

The reservoir may be coupled to the conductor 18 in any suitable manner and for the purpose of illustration two coupling means are shown.

Leading from the reservoir 19 near its lower portion and preferably at one side, is a relatively small discharge tube 22 upturned near its free end as shown at 23 and provided with a relatively small discharge nozzle or mouth-piece represented as a whole at 24. The discharge 24 will be located a sufficient distance above the handle of the valve 16 so that it does not interfere with the operation of the same. The pipe 22 is provided with a suitable drain 25 to permit the discharge of water from said pipe and thus prevent freezing.

The presence of the drinking fountain attachment does not interfere with the ordinary uses of the spout 14, through which the water is free to pass when the valve 16 is opened. When the fountain is to be used the valve 16 is closed and the water forced through the tube 18 by the operation of the pump to supply the reservoir, and from thence flows to the mouth-piece 24 in the usual manner. If the improved device is applied to a force pump, and the water supply in the air chamber is sufficient, the reservoir 19 will be filled therefrom. If the improved device is applied to an ordinary pump, the operator closes the valve 16 and operates the pump handle a few strokes to cause a supply of water to be conducted to the reservoir to supply the drinking fountain.

If the water in the reservoir is not entirely consumed, the surplus water automatically drains back through suitable openings 19' into the tube 18, thus preventing the accumulation of water in the reservoir and avoiding freezing in cold weather.

It will be noted by this arrangement that the main spout 14 is available at all times for use in connection with the pump and the only requisite required to change the device into a drinking fountain is to close the cut-off valve 16 and operate the handle of the pump a few strokes.

The improved device is entirely sanitary and the drinker is protected from contamination.

The improved device is simple in construction, can be inexpensively manufactured and adapted to pumps of various sizes and forms without structural change in the 5 pump except to discard the ordinary spout and apply the improved spout with the same fastening devices used for securing the ordinary spout.

Having thus described the invention, what 10 is claimed as new is:

1. The combination with a discharge spout having a cut-off valve, of a reservoir having a closure, a conductor having one end thereof communicating with the discharge spout 15 at a point between the valve and the source of supply and its other end extended within the reservoir to a point beneath the closure thereof, a mouth-piece and a downwardly inclined conductor forming a connection between the reservoir and mouth-piece.

2. The combination with a pump cylinder, of a discharge spout having a cut-off valve and provided with an attaching flange detachably secured to the pump cylinder, a 25 reservoir, a conductor communicating with and extending above the discharge spout between the cut-off valve and the source of supply and extending within the reservoir to a point near the top thereof and provided with drain openings, a mouth-piece and a conductor leading from the reservoir 30 near the drain openings and communicating with said mouth-piece.

3. The combination with a discharge spout 35 having a cut-off valve, of a reservoir having a closure, a conductor communicating with the discharge spout at a point between the valve and the source of supply and connected with the reservoir, a pipe connected 40 with the conductor and extending within the reservoir to a point near the closure thereof, said pipe being provided with drain

openings, a mouth-piece, a downwardly inclined conductor forming a connection between the reservoir and mouth-piece, and a 45 drain formed in the last-mentioned conductor at a point beneath the mouth-piece.

4. The combination with a discharge spout having a cut-off valve, of a conductor communicating with the discharge spout between the cut-off valve and the source of supply and having its upper end threaded in the opening in the reservoir and provided with an annular shoulder bearing against the bottom of the reservoir, a pipe connected with the threaded end of the conductor and extending to a point near the closure of the reservoir, said pipe being provided with drain openings, a mouth-piece and a downwardly inclined conductor forming a source of communication between the bottom of the reservoir and said mouth-piece.

5. The combination with a discharge spout having a cut-off valve and provided with an upstanding internally threaded nipple 70 disposed between the cut-off and the source of supply, an upstanding conductor threaded in said nipple and supported by said spout, a reservoir mounted on and supported by the conductor, a pipe connected with the conductor and extending within the reservoir to a point near the top thereof, a mouth-piece, a conductor forming a source of communication between the lower portion 75 of the reservoir and the mouth-piece, and a drain located in the last-mentioned conductor at a point below said mouth-piece.

In testimony whereof I affix my signature.
GEORGE H. BELL. [L.S.]
